US0D1097167S

(12) **United States Design Patent** (10) **Patent No.:** **US D1,097,167 S**
(45) **Date of Patent:** **** Oct. 7, 2025**

(54) **PRESSURE OFFLOADING DEVICE**

(71) Applicant: **Recovery Force Health, LLC**, Fishers, IN (US)

(72) Inventor: **Kevin Nelson**, Brunswick, OH (US)

(73) Assignee: **Recovery Force Health, LLC**, Fishers, IN (US)

(**) Term: **15 Years**

(21) Appl. No.: **29/841,276**

(22) Filed: **Jun. 3, 2022**

(51) LOC (15) Cl. **24-02**

(52) U.S. Cl.

USPC **D24/189**

(58) **Field of Classification Search**

USPC D24/188, 189, 191–193, 200, 203, 213; D28/4, 7, 99

(57) **CLAIM**

The ornamental design for a pressure offloading device as shown and described.

DESCRIPTION

FIG. 1 is a perspective view of a pressure offloading device showing my new design;

FIG. 2 is a left side view thereof;

FIG. 3 is a right side view thereof;

FIG. 4 is a front end view thereof;

FIG. 5 is a rear end view thereof;

FIG. 6 is a top view thereof;

FIG. 7 is a bottom view thereof; and

FIG. 8 is a perspective view thereof with the strap connected to the opposing side.

FIG. 9 is a perspective view of a pressure offloading device showing my new design;

FIG. 10 is a left side view thereof;

FIG. 11 is a right side view thereof;

FIG. 12 is a front end view thereof;

FIG. 13 is a rear end view thereof;

FIG. 14 is a top view thereof;

FIG. 15 is a bottom view thereof; and

FIG. 16 is a perspective view thereof with the strap connected to the opposing side;

FIG. 17 is a perspective view of a pressure offloading device showing my new design;

FIG. 18 is a left side view thereof;

FIG. 19 is a right side view thereof;

FIG. 20 is a front end view thereof;

FIG. 21 is a rear end view thereof;

FIG. 22 is a top view thereof;

FIG. 23 is a bottom view thereof; and,

FIG. 24 is a perspective view thereof with the strap connected to the opposing side.

In the drawings, the broken lines show portions of a pressure offloading device that form no part of the claim.

1 Claim, 24 Drawing Sheets
